UNITED STATES PATENT OFFICE.

ALBERT J. PITKIN AND JAMES E. SAGUE, OF SCHENECTADY, NEW YORK.

COMPOUND ENGINE.

SPECIFICATION forming part of Letters Patent No. 592,824, dated November 2, 1897.

Application filed May 21, 1897. Serial No. 637,592. (No model.)

To all whom it may concern:

Be it known that we, ALBERT J. PITKIN and JAMES E. SAGUE, citizens of the United States, residing at Schenectady, in the county 5 of Schenectady and State of New York, have invented certain new and useful Improvements in Compound Engines, of which the following is a specification.

Our invention relates to the class of compound engines which are organized to start with live steam in both the high and low pressure cylinders and automatically change to operate with live steam in the high-pressure cylinder and exhaust-steam in the low-pressure 10 sure cylinder and which have provisions whereby the engine may be run by live or high-pressure steam in both cylinders whenever desired and for any desired length of time. 15 Locomotive-engines organized to operate in this way are most efficient, and there is much economy in the expense of operation. The use of live steam in both cylinders at starting insures the immediate operation of the 20 mechanism to set the locomotive in motion, which can then under ordinary conditions run compound, and thus economize in the use of steam. When extraordinary service is required, as when ascending grades, it is desirable 25 to operate with increased power, and hence live steam is used in both cylinders. It is important that the mechanism shall be so constructed and organized that the changes from simple to compound or from compound 30 to simple may be quick, accurate, and automatic.

The object of our invention is to provide simple, positive, and automatic mechanism for starting compound locomotives of this 40 class, reliably-acting means for automatically changing from simple to compound after the engine is started, and improved mechanism for changing from compound to simple working or to cause the engine to run as a 45 simple engine for any desired length of time.

We employ an intercepting-valve which opens or closes the steam-passage from the high-pressure cylinder to the low-pressure cylinder and which also governs the admission 50 of live steam direct to the low-pressure cylinder when communication between the

high-pressure cylinder and low-pressure cylinder is cut off. We employ an exhaust-valve of an improved construction whereby the exhaust-steam from the high-pressure cylinder may pass to the atmosphere when both cylinders are receiving live steam and the engine is running continuously as a simple engine. 55

We do not wish it understood that we claim, broadly, a supplemental exhaust-valve in a compound engine involving the use of an automatic intercepting-valve, nor do we claim as our invention, broadly, an engine organized to work at will as a compound engine or 60 as a simple engine, but we claim to have made certain improvements in the details of construction and in the operation of the valves whereby the engine is made to work 65 more smoothly and with greater efficiency. 70

In the accompanying drawings, Figure 1 is a vertical transverse section through the smoke-box of a locomotive and the cylinders and cylinder-saddles, the intercepting-valve chamber being shown on the low-pressure side 75 of the engine. Fig. 2 shows a vertical longitudinal section on the line 2 2 of Fig. 1 and illustrates particularly the steam-admission pipes and the receiver-pipe. Fig. 3 is a longitudinal sectional view, on an enlarged scale, 80 through the intercepting-valve, the auxiliary exhaust-valve, and their case, the parts being shown in the position they occupy when the engine is running simple—that is to say, when live steam is being admitted to both the high-pressure and low-pressure cylinders. Fig. 4 is a similar view showing the parts in another 85 position—viz., that in which they are arranged when the engine is working compound. Fig. 5 shows a transverse section on the line 90 5 5 of Fig. 4. Fig. 6 shows a similar section on the line 6 6 of Fig. 4, and Fig. 7 shows a transverse section on the line 7 7 of Fig. 3.

The high-pressure cylinder A and the low-pressure cylinder B are connected by a receiver-pipe C in the usual way. High-pressure or live steam enters through the pipe D and passes to the high-pressure cylinder through pipe E and to the low-pressure cylinder through branch pipe F. The exhaust 95 from the low-pressure cylinder passes out through the nozzle G. 100

The parts just described are all of well-known construction and need no detailed description.

The intercepting-valve II is a slide-valve 5 and is located in the saddle of the low-pressure cylinder, as in Pitkin's patent No. 417,083, of December 10, 1889. The passage I, connecting the valve-chest of the low-pressure cylinder with the receiver, is bridged by a 10 guide K for the intercepting-valve. This valve is hollow or chambered, being closed at its front end h, at which end it is provided with a forwardly-projecting annular flange l, having an opening l' for the passage of steam 15 from the high-pressure cylinder, as herein-after described. The portion h' of the intercepting-valve is solid, and the portion II' in rear of the solid portion h' is made hollow or chambered, but it has a web h², provided 20 with a perforated abutment h³ for the reducing-valve M.

The intercepting-valve is provided with lateral openings N, which communicate with the hollow or chambered portion of the valve 25 and at times communicate with openings n, leading to the steam-chest of the low-pressure cylinder or to a passage n', which communicates with said steam-chest. Packing-rings n² are let into the outside of the intercepting-valve on one side of the openings N, and a packing ring or groove n³ may be arranged 30 on the opposite side of said openings N. This is to prevent the escape of live steam into the receiver when the engine is working 35 on the compound principle. Preferably a bushing N² is used around the intercepting-valve, as in Pitkin's patent before referred to.

The rear portion of the valve II is reduced 40 in diameter and works in a casing or bushing N³, which, when desired, may be removed from the shell or casing N⁴. The rear portion of the valve is provided with lateral openings n⁴, communicating with the interior of the valve and also with the live-steam chamber 45 N⁵, which is connected with the pipe F. (Indicated in Figs. 1 and 2.)

The reducing-valve M is arranged close to the openings n⁴ and is arranged to slide in guides o and in a cylindrical boss O, formed 50 on an end piece O', which is removably secured to the rear end of the intercepting-valve. The smaller end of the reducing-valve works back and forth in the cylindrical boss, and a piston o' within the cylindrical boss extends 55 into a cylindrical opening in the reducing-valve. This arrangement acts as a dash-pot to cushion the movement of the reducing-valve, which would otherwise vibrate too rapidly and hammer badly. The rear end of the 60 intercepting-valve may be packed with metallic rings or other packings o², and it is provided with an escape-opening O³ in rear of the reducing-valve to permit the escape of steam or condensed vapor should there be any 65 leakage. A drip-pipe o³ is also provided to carry off condensed steam when necessary.

The opposite or larger end of the reducing-valve when it is open abuts against the perforated abutment h³. When the reducing-valve is closed, as in Fig. 4, its larger end coincides or registers with an annular flange o⁴. 70

A dash-pot P, similar to that shown in Pitkin's patent No. 417,083, is employed to regulate the movement of the intercepting-valve. The rod P' is connected to the valve by a taper-joint and removable key p. The piston-head p' is guided and prevented from turning by a feather-and-groove connection p². By this arrangement the intercepting-valve is also prevented from turning and the several 75 steam-ports are kept in proper alinement. Ground joints are employed wherever required, and packing-rings are also employed at such places as would be apt to leak. The particular manner of packing the joints is not 80 important. The dash-pot is removable from the end of the intercepting-valve casing, and the piston-rod P' may be readily detached, as may also the end of the intercepting-valve, so that the reducing-valve may be withdrawn 85 for examination or repair. 90

The auxiliary exhaust-valve is arranged at the front end of the intercepting-valve. The casing Q is bored centrally in line with the intercepting-valve to receive a cage R, in 95 which the auxiliary exhaust-valve is arranged to slide. The cage is flanged at r and removably secured to the casing Q. It has a front chamber r', within which slides a piston-head r², and a back chamber r³, which communicates with a central opening r⁴, leading into the receiver, and with lateral openings r⁵, connecting with a chamber or passage S, which leads to the main exhaust G. The larger member R² of the valve has a ground seat r⁶ on 105 the back end of the cage, and it is formed with guide-wings r⁷, which slide within the chamber r³. The stem r⁸ of the valve member R² is hollow and extends back into the chamber r'. The hollow or chambered portion is open 110 at r⁹ and is provided with lateral openings r¹⁰ within the chamber r³.

A valve member T of comparatively small area has a valve-seat t at the rear end of the chambered portion of the valve member R². 115 It has a stem T' extending through the chambered stem r⁸, and the front end of the stem is connected with the piston-head r² by a tapered joint and a nut r¹². A spiral spring U surrounds the hollow valve-stem r⁸ and bears 120 against the flange or partition u between the front and back chambers r' and r³ and against the piston-head r². This spring is put in place under considerable initial pressure and holds both valves closed when there is no counteracting pressure. There is a space between the piston-head r² and the end r¹⁰ of the hollow stem r⁸, so that the valve T may move for a short distance independently of the valve member R². A chamber V is formed in the 125 front of the piston-head r², and with this chamber communicates a steam-pipe v, which 130

leads to the cab. By causing steam, air, or other fluid to pass through this pipe the piston may be moved rearwardly, first causing the valve member T to open and then opening the valve member R². When this occurs, there will be a communication between the receiver and the exhaust-passage S.

The valve in the cab is so arranged that it can be turned either to admit the operating fluid to the chamber V or to permit the exhaust of fluid therefrom. Such valves are of well-known construction and need no further description. There is, however, a liability of these valves leaking, and in order to prevent any accidental accumulation of pressure in front of the piston r² we provide a leakage-groove x in the chamber r'. This groove is made large enough to relieve any pressure due to such leakage, but it is not large enough to prevent the piston r² from being operated when the valve in the cab is opened wide. The groove is especially essential when the auxiliary exhaust-valve is operated by steam, as without it a slight leakage of the valve in the cab would cause the chamber V or r' to be filled with condensed steam. As shown in Fig. 4, the groove x is longer than the piston r², and there is a free passage from one end of the piston to the other when the auxiliary exhaust-valve is closed. Any leakage past the piston escapes through an opening x'. In order to protect the parts at the front of the apparatus, we provide a shell or casing W, which may be attached, as indicated, to the flange r and to the end piece R' of the cage. The flange l on the intercepting-valve is adapted to be seated, when this valve is closed, in an annular seat l¹¹.

In starting the engine the position of the intercepting-valve and the auxiliary exhaust-valve will be as indicated in Fig. 4. Live steam from the main throttle-valve is admitted into the high-pressure cylinder through the main steam-pipe E, and at the same time through the pipe F to the back of the intercepting-valve chamber. The live steam enters the chamber N⁵, passes through the openings N, and moves the intercepting-valve forward into the position shown in Fig. 3, (the auxiliary exhaust-valve, however, being closed).

When the intercepting-valve has almost reached its point of full forward travel, it opens the ports n in the bushing N² and steam passes through the reducing-valve M and openings n into the chamber n', and thence to the steam-chest of the low-pressure cylinder. The high-pressure steam, acting upon the opposite ends of the reducing-valve, which have different areas, moves the valve forward and opens the passages, as shown. The live steam after passing the reducing-valve exerts its reduced pressure on the full area of the large piston of the reducing-valve, tending to move this valve back and throttle the admission of steam. The sizes of the op-

posite ends of the reducing-valve are so proportioned that the difference of the areas against which the high-pressure steam acts is about one-half of the area of the large piston which is acted upon by the reduced pressure. The steam supplied to the low-pressure cylinder is thus reduced in the ratio required to suit the relative areas of the high and low pressure cylinders and enable them to exert equal power when running simple. High-pressure steam thus being supplied to the high-pressure cylinder through the main steam-pipe and steam at reduced pressure to the low-pressure cylinder through the intercepting and reducing valves, the engine starts with the intercepting-valve closed, the communication between the low-pressure cylinder and the receiver being cut off.

The high-pressure cylinder exhausts into the receiver and accumulates pressure upon the front end h of the intercepting-valve. The area of this end h of the intercepting-valve is so proportioned in relation to the difference of areas at the back of the intercepting-valve that the intercepting-valve is moved by receiver-pressure when this pressure has accumulated sufficiently to give the full required power to the low-pressure piston. This occurs after one or two exhausts from the high-pressure cylinder. After the intercepting-valve is started the flange l is moved from its seat l¹¹, and then the valve slides quickly back to its extreme rear position, as pressure is then exerted upon the full area of the front of the valve, including the flange l. When the intercepting-valve is thus moved, the supply of live steam to the low-pressure cylinder is cut off, communication is opened between the receiver and the steam-chest of the low-pressure cylinder, and the latter is then supplied with steam from the receiver. The locomotive will then run as a compound engine. When thus operated, the pressure equalizes around the larger piston of the reducing-valve, pressing it firmly against its seat at the back, and all leakage is practically prevented. The intercepting-valve is also held back firmly by receiver-pressure, and the joints and packing are such as to prevent escape of steam.

The auxiliary exhaust-valve is not used in ordinary starting and remains closed, as shown in Fig. 4. The engine may be repeatedly started and stopped without bringing into operation the auxiliary exhaust-valve; but in case it is desired to run the engine "simple" steam or air is admitted from a three-way valve in the cab through the pipe v to the chamber V in front of the piston-head r². This moves the head back and first opens the valve member T and then the larger valve member R², permitting the steam from the receiver to pass into the back chamber of the cage R and out through passage S.

At the first reduction of pressure in the receiver the live-steam pressure at the back of

the intercepting-valve forces this valve forward against its seat l^1 and communication between the receiver and the low-pressure cylinder is cut off. The low-pressure cylinder is then supplied with steam at reduced pressure through the intercepting and reducing valves, as previously described, for automatic starting, and the engine runs simple, with the valves in the position shown in Fig. 10 3, as long as desired.

The advantage of employing the smaller valve member T is that it affords a means of reducing the receiver-pressure gradually in case the receiver is filled with steam at the 15 normal pressure, thus avoiding a violent exhaust and permitting the large valve member R^2 to be opened more easily than it could be against full receiver-pressure.

When it is desired to resume compound 20 working, the position of the valve in the cab is changed, allowing the air or steam to exhaust from the front chambers r' and V , and the spring U will force the valve members back to their seats. Receiver-pressure then 25 accumulates, opens the intercepting-valve, and shuts off the independent supply of live steam to the low-pressure cylinder, as in automatic starting. During compound working the valve members R^2 and T are held 30 firmly against their seats by receiver-pressure, as well as by the spring U .

A collar y on the valve-stem T' guides the stem, and forward movement of the piston-head r^3 is limited by an annular shoulder y' 35 in the chamber r' , and the flange l serves not only to shut off communication between the receiver and the steam-chest of the low-pressure cylinder, but also to direct the passage 40 of exhaust-steam from the receiver to the auxiliary exhaust.

The auxiliary exhaust-valve, it will be observed, comprises two parts or members R^2 and T . Both coact to effect the same result, but the independent actuation of the smaller 45 member T modifies the action, as above explained. The amount of independent movement of the valve member T is regulated by the distance between the head r^2 and the end 50 of the valve-stem r^s when the valves are closed.

We claim as our invention—

1. In a compound engine the combination 55 of the high and low pressure cylinders, a receiver-pipe connecting them, an intercepting-valve interposed between the two cylinders, a reducing-valve within the intercepting-valve, an auxiliary exhaust-valve composed of two independently-movable parts, and means for actuating one part to partially open the auxiliary exhaust-passage, and for subsequently actuating the other part to further open said passage.

2. In a compound engine, the combination 60 of the high and low pressure cylinders, the receiver-pipe connecting them, a chambered intercepting-valve interposed between the

two cylinders and formed with ports for the entrance and exit of live steam and provided with a removable end piece having a chambered boss for guiding a reducing-valve, a 70 reducing-valve within the chambered intercepting-valve, an abutment within said chamber for the reducing-valve, an annular flange with which the larger end of the reducing-valve at times registers, a dash-pot, its piston, a feather-and-groove connection between the piston-head and the dash-pot casing, a tapered joint between the piston-rod and the removable end of the intercepting-valve, a key for attaching the rod to the end of the 80 intercepting-valve, packings to prevent the passage of steam, drip-apertures and escape-pipes, and an auxiliary exhaust-valve for the exhaust from the high-pressure cylinder. 75

3. In a compound engine, the combination 85 of the high and low pressure cylinders, a receiver-pipe connecting them, an intercepting-valve, means for operating it automatically, and an auxiliary exhaust-valve consisting of two independently-movable parts, the smaller 90 one of which is adapted to be opened before the larger, to reduce the receiver-pressure gradually and avoid a violent exhaust, substantially as described.

4. The combination of the intercepting-valve, and the auxiliary exhaust-valve comprising the larger member having a hollow stem, the smaller member having a stem moving within the hollow stem of the larger member, a piston-head to which the stem of the 100 smaller member is connected, and a spring for closing both members. 95

5. The combination of the cage of the auxiliary exhaust, the larger member of the exhaust-valve, its hollow stem having a rear 105 opening and one or more lateral openings, the smaller member having a stem arranged within the hollow stem of the larger member, a piston-head secured to the stem of the smaller member, and a spring under pressure 110 interposed between the piston-head and the cage and a port for the admission of fluid-pressure to the front end of the piston.

6. In a compound engine the combination 115 of the high and low pressure cylinders, a receiver-pipe connecting them, an intercepting-valve interposed between the high and low pressure cylinders, a flange l projecting forwardly from the intercepting-valve and having an edge of reduced area fitting a closed or steam-tight seat l^1 , said flange being also provided with a lateral opening through 120 which steam passes from the receiver to an auxiliary exhaust, and having a closed portion closing a passage between the receiver and 125 the low-pressure cylinder.

7. In a compound engine, the combination 130 of the intercepting-valve, the cage for the auxiliary exhaust-valve provided with front and back chambers, the larger member of the auxiliary valve having a hollow stem and provided with guide-wings sliding in the back

chamber of the cage, the smaller member of
the auxiliary exhaust-valve having a stem ar-
ranged within the hollow stem of the larger
member, a piston-head secured to the stem of
5 the smaller member and arranged in the front
chamber of the cage and a spring for closing
both members of the valve.

In testimony whereof we have hereunto
subscribed our names.
